GARTER

Filed Nov. 19, 1930

FIG. 1.

FIG. 2.

FIG. 3.

INVENTOR:

BENZION WOLF

By Clever, Cox & Moore

ATKGS.

UNITED STATES PATENT OFFICE

BENZION WOLF, OF CHICAGO, ILLINOIS

GARTER

Application filed November 19, 1930. Serial No. 496,575.

My invention relates generally to garters, and more particularly to garters of the type adapted to be applied to the ankle of the wearer.

5 It is one of the primary objects of my present invention to provide a garter of the type set forth above having improved, novel arrangement for adjustably securing a reinforcing member within a pocket of the garter 10 element extending vertically from the band encircling the wearer's ankle.

Another object of my invention is to provide a garter of extremely simple construction which is adapted to be conveniently adjusted in accordance with the length of the wearer's sock, and to this end I propose to provide a simple two-piece upright element which is arranged in a novel and practical manner for adjustably receiving and supporting a keeper.

More specifically, my invention contemplates the provision of a garter as set forth above in which the upright element extending from the ankle encircling band is formed 25 with an intermediate opening so as to enable the convenient mounting and adjusting of a keeper and also to facilitate the insertion and removal of a reinforcing insert.

It is still a further object of my invention 30 to provide, in combination with the garter set forth above, improved side supports for the upright element, which supports serve to effectively maintain the proper vertical position of said upright element when in use.

35 The foregoing and numerous other objects and advantages will be more apparent from the following detailed description when considered in connection with the accompanying drawing, wherein:

40 Fig. 1 is a perspective view disclosing a garter embodying features of my invention, applied to the leg of a wearer;

Fig. 2 is an enlarged perspective view disclosing the garter of Fig. 1, the reinforcing 45 insert being partially withdrawn in order to more clearly disclose the intermediate opening provided in the upright garter element; and

Fig. 3 is an enlarged sectional view taken 50 substantially along the line 3-3 of Fig. 1,

the supported sock being shown by dotted lines in order to more clearly visualize the structural arrangement of the garter.

Referring now to the drawing more in detail wherein like numerals have been employed to designate similar parts throughout the various figures, it will be seen that one embodiment of my invention includes a garter having a band 10 of suitable flexible material which is adapted to be applied immediately above or adjacent the wearer's ankle as clearly shown in Fig. 1. The length of the encircling portion of the band 10 is adapted to be adjusted by means of a suitable buckle 12 and extending upwardly from and secured to said band is an upright support or garter element which I have designated generally by the numeral 14. This upright member or support 14 comprises a pair of strips 16 and 18, which are stitched along their margins so as to present between said strips an elongated pocket 20 for receiving a suitable reinforcing strip 22 preferably formed of flexible material.

Attention is directed to the fact that in a section of the strips 16 and 18 of the support member 14 which is designated by the bracket A, the stitches are omitted, thereby presenting open sides which permit of the convenient insertion or removal of the reinforcing strip 22. In Fig. 2 I have disclosed the reinforcing strip 22 partially withdrawn in order to more clearly illustrate this open sided portion extending over the length designated by the bracket A.

By having this open sided arrangement extending over the length A I am able to conveniently adjust the position of a keeper 24 which is slidably mounted on the unstitched portion of the strip 18. A buckle or fastening means 26 is mounted upon the upright member 14 immediately above the unstitched portions thereof as clearly shown in Figs. 2 and 3. This buckle 26 is positioned so as to bind the strips 16 and 18 against the upper end of the flexible insert 22 and thereby preventing any creeping or relative movement between said insert and said strips. This is clearly shown in Fig. 3 where the buckle 26 provides an abutment which prevents any upward

movement of the insert 22 or downward movement of the strips 16 and 18 with respect to said insert.

From the foregoing it will be seen that the upright member or support 14 is of extremely simple construction and may be formed by selecting a single strip of suitable material, folding it intermediate its ends, applying a clasp 28 at the folded portion, and then stitching the portion of the strips which extends between the unstitched section A and the clasp 28 as clearly shown in Fig. 2. The buckle 26 may then be applied and the unstitched portion of the strip 18 may now be threaded through the keeper 24 and the remaining portions of the strips 16 and 18 stitched together and secured at their lower extremities to the band 10. The flexible insert 22 may then be inserted. It should be understood that the steps defined above may be practiced in various ways in order to produce the same result, namely an upright flexible support or garter element in which a portion thereof is provided with an intermediate opening which serves to permit of the convenient mounting and adjustment of the keeper 24 and also serves to facilitate the insertion or removal of the flexible insert 22.

In order to further secure the upright support 14 against lateral displacement when in use by the wearer, I provide braces 30 which are secured at their lower extremities to the band 10 on opposite sides of the support 14 and which are secured at their upper extremities to said upright support at a point adjacent the adjustable buckle 26. By having these braces 30 extending from the band 10 to a point positioned well above said band, I am able to very effectively prevent lateral displacement of the upright support 14. By securing the upright member or support 14 against lateral displacement in the manner described above, I am able to maintain the flexible insert 22 in its normal upright position and thereby cause a sock 32 of the wearer to be secured in proper wearing position at all times.

From the foregoing it will be apparent that if it is desired to adjust the garter to be used for a sock of a different length from that shown in the drawing, it is only necessary to shift the keeper 24 along the unstitched portion of the strip 18 which supports it. Likewise, if it is desired to use a flexible insert differing in length from that shown in the drawing, it is only necessary to adjust the position of the buckle 26.

This garter has been placed in practical use and has proven very successful. The flexible side supports or braces cooperate with the central supporting member or strip to firmly secure said support against displacement, and the adjustability of the keeper 24 and the buckle 26 enables the garter to be used with

garments such as socks which vary in size over a comparatively wide range.

While I have disclosed a particular embodiment of the invention, it should be understood that said invention is by no means limited to the specific structural features shown in the drawing, but is capable of numerous other modifications and variations without departing from the spirit and scope of the appended claims.

Having thus described my invention, what I claim as new and desire to secure by Letters Patent is:

1. In a garment support of the class described, a flexible band adapted to be applied above the ankle of a wearer, a supporting means secured to and extending upwardly from said flexible band, said supporting means including an elongated fabric strip provided with an elongated pocket and a reinforcing member inserted within said pocket for lending rigidity to said supporting means, said fabric strip having an intermediate opening whereby to present a strip portion, a keeper adjustably mounted on said strip portion, and a garment supporting device secured to the upper extremity of said supporting means for cooperating with said keeper in securing a garment in position.

2. In a garment support of the class described, a flexible band adapted to be applied above the ankle of a wearer, a supporting means secured to and extending upwardly from said flexible band, said supporting means including an elongated fabric strip provided with an elongated pocket and a reinforcing member inserted within said pocket for lending rigidity to said supporting means, an intermediate portion of said pocket having an external opening whereby to present a free portion of the strip, a keeper adjustably mounted on the free portion of said strip, and a garment fastening device secured to the upper extremity of said supporting means which is adapted to cooperate with said keeper in securing a garment in position.

3. In a garment support of the class described, a flexible band adapted to be applied above the ankle of a wearer, a supporting means secured to and extending upwardly from said flexible band, said supporting means including an elongated fabric strip provided with an elongated pocket and a reinforcing member inserted within said pocket for lending rigidity to said supporting means, said fabric strip having an intermediate opening whereby to present a strip portion, a keeper adjustably mounted on said strip portion, a garment supporting means for cooperating with said keeper in securing a garment in position, and adjustable closure means extending across the upper portion of said pocket at a point adjacent the upper extremity of said reinforcing member to prevent any appreciable

relative movement between the fabric strip and the reinforcing member.

4. In a garment support of the class described, a flexible band adapted to be applied above the ankle of a wearer, a supporting means secured to and extending upwardly from said flexible band, said supporting means including an elongated fabric strip provided with an elongated pocket and a reinforcing member inserted within said pocket for lending rigidity to said supporting means, said fabric strip having an intermediate opening whereby to present a strip portion, a keeper adjustably mounted on said strip portion, a garment supporting device secured to the upper extremity of said supporting means for cooperating with said keeper in securing a garment in position, and braces positioned on opposite sides of said supporting means to secure the same against lateral displacement.

5. In a garment support of the class described, a flexible band adapted to be applied above the ankle of a wearer, a supporting means secured to and extending upwardly from said flexible band, said supporting means including a pair of fabric strip sections stitched along their outer margins so as to present an internal elongated pocket, a flexible reinforcing strip within said pocket, a portion of the stitchings being omitted along an intermediate portion of the supporting strips, a keeper adjustably mounted upon one of the unstitched portions of said strip, and a garment fastening device secured to the upper extremity of said supporting means adapted to cooperate with the keeper in securing a garment in position.

In witness whereof, I have hereunto subscribed my name.

BENZION WOLF.
